UNITED STATES PATENT OFFICE

141,596

DESIGN FOR A BOOK STAND OR SIMILAR ARTICLE

Howard H. Thompson, Santa Cruz, Calif.

Application March 27, 1945, Serial No. 118,729

Term of patent 14 years

(Cl. D33—10)

To all whom it may concern:

Be it known that I, Howard H. Thompson, a citizen of the United States, residing at Santa Cruz, in the county of Santa Cruz and State of California, have invented a new, original, and ornamental Design for a Book Stand or Similar Article, of which the following is a specification, reference being had to the accompanying drawing, forming part thereof.

Figure 1 is a perspective view of a book stand or similar article, showing my new design,

I claim:

The ornamental design for a book stand or similar article, as shown.

HOWARD H. THOMPSON.
